UNITED STATES PATENT OFFICE

103,716

DESIGN FOR A BLOUSE OR SIMILAR ARTICLE

Florence Hudson Enscore, New York, N. Y.

Application December 2, 1936, Serial No. 66,262

Term of patent 3½ years

To all whom it may concern:

Be it known that I, Florence Hudson Enscore, a citizen of the United States, residing at New York City, in the county and State of New York, have invented a new, original, and ornamental Design for a Blouse or Similar Article, of which the following is a specification, reference being had to the accompanying drawing, forming a part thereof, and in which

Fig. 1 is a front elevation, partly in outline and partly in detail to show the design of the front of the blouse; and

Fig. 2 is a rear elevation, partly in outline and partly in detail to show the design of the back of the blouse.

I claim:

The ornamental design for a blouse or similar article, substantially as shown.

FLORENCE HUDSON ENSCORE.
